EASY OPEN CARTON

John V. Mahon, Lansdale, Pa., assignor to Container Corporation of America, Chicago, Ill., a corporation of Delaware

Filed June 17, 1966. Ser. No. 558,456
4 Claims. (Cl. 229—51)

ABSTRACT OF THE DISCLOSURE

An easy open carton having a tear strip formed in one minor side wall along and about the lapped panels of the manufacturer's joint.

This invention relates to a paperboard carton having a tear strip opener, and more particularly, to an improved manner of forming the tear strip on the manufacturer's or lapped joint of the carton.

Tear strip openers are common as a means for opening paperboard cartons. The tear strip is generally formed between a pair of spaced weakened lines made in one of the panels of the carton, and appropriate means at one or both ends of the strip provide initial access to the strip. Conventionally, cartons used for such products as frozen foods or the like, have incorporated a tear strip construction in the end closure flaps or panels of the carton which are overlapped for closing the carton.

Difficulty in closing cartons of this style have occurred in that the closure flaps, being perforated with weakened lines, are no longer rigid and cannot be readily folded over by automatic flap folding means. Thus, a common defect occurring in the sealing of the carton of this general style is that the closure flaps do not overlap flush with one another but bulge or buckle across their widths. This bulge in one or both of the flaps causes improper flap sealing and thus renders a carton defective in both appearance and function.

This invention contemplates forming the tear strip in a paperboard carton in the area of the lapped manufacturer's joint of the tubular carton. The end closure flaps formed at the opposite ends of the tubular carton body thus are whole and are not weakened by cut lines being formed therein. The carton thus can be readily formed from the tubular body, as required, by folding the end closure flaps over 90° into overlapped relation and securing them together by heat sealing, adhesive or other equivalent means.

Accordingly, an object of this invention is to provide in a tubular carton an improved tear strip opener located along the lapped manufacturer's joint.

Another object of this invention is to provide a tubular carton having a tear strip extending across the width of the paperboard blank forming the carton, and having end closure flaps for the tubular carton that are generally free from weakened lines of tear.

These and other objects of this invention will be more fully understood after reviewing the following specification and the accompanying drawing forming a part thereof, wherein:

FIG. 1 is a perspective view of a carton incorporating a first embodiment of the subject invention;

FIG. 2 is a top plan view of a blank suitably cut and scored to form the carton disclosed in FIG. 1;

FIG. 3 is a perspective view of a partially erected carton of the type shown in FIG. 1, the end closure flaps being shown in the opened condition;

FIG. 4 is a sectional view as seen generally from line 4—4 of FIG. 1, except with the tear strip being shown in a partially severed condition; and

2

FIG. 5 is a perspective view, similar to FIG. 3, of a second embodiment of the subject carton construction.

The carton 10 shown is a typical carton for frozen foods or the like and includes opposed top and bottom major wall panels 12 and 14 respectively; opposed front and rear minor wall panels 16 and 18 respectively; and opposed end minor wall panels 20. The carton walls are hinged together at the adjacent end edges thereof to define thereby an enclosure as is well known in the art.

10 A tear strip 24 is defined along one minor wall panel of the carton between a pair of parallel weakened lines 26 and 27. An additional weakened line 28 is formed in one wall panel adjacent the tear strip wall panel and is immediately adjacent the end of the tear strip 24 to permit initial opening of the carton by depressing tab 29 within the weakened line 28 and thereafter ripping the exposed end of the tear strip.

A blank 34 is shown in plan view in FIG. 2 which is appropriately cut and scored to define the carton 10. The

20 blank 34 is generally elongated and includes a pair of spaced score lines 36 and 37 extended parallel to one another along generally opposite longitudinal edges of the blank. Transverse score lines 40, 41, 42 and 43 are extended across the blank between the score lines 36 and 25 37 and divide the blank into a plurality of panels suitable for forming the various walls of the carton. Thus, the blank is divided into an inner front wall panel 46, the top wall panel 12, the rear wall panel 18, and an outer front wall panel 47. End closure flaps are hinged to the end 30 edges of the respective side wall panel constructions on score lines 36 and 37, and include the inner end wall flaps 50, 51 and 52 hinged to the opposite end edges of the inner front wall panel 46, the rear panel 18, and the outer front wall panel 47, respectively; and outer end wall flaps 35 54 and 55 hinged to the opposite end edges of the major wall panels 12 and 14, respectively. The flaps 50—55 are separated from one another by cut lines from the longitudinal score lines 36 or 37 to the edge of the blank.

The carton is initially formed into a tubular structure

40 by folding the top and inner front wall panel upwardly about the score line 40 (FIG. 2) and thereafter folding the outer front wall panel 47 about the score line 43 to overlap the marginal end edges of the front wall panels. The marginal edges are suitably adhered to one another 45 by appropriate means such as adhesives, heat sealing or the like so that the front wall 16 of the carton is double ply and is formed by the marginal end edges of this manufacturer's joint of the carton. The tubular body as thus defined by the lapped and joined inner and outer front wall panels, and the top, rear and bottom side walls is thus ready to be loaded with product and have the end flaps closed and sealed. The inner end wall flaps are folded inwardly across the open end of the tubular structure first (FIG. 3), and thereafter the outer end wall flaps 50 54 and 55 are folded inwardly over the inner end wall flaps and into overlapping relation to one another and are secured in place by heat sealing, adhesives or the like.

The subject invention includes forming the tear strip 24 between the weakened lines 26 and 27 which are located on the respective front wall panels adjacent the joined lapped manufacturer's joint of the tubular structure.

Thus, the end flaps are not weakened to any great extent by lines of weakness formed therein to thereby permit them to be folded over across the open end of the tubular body incident to the loading and closing of the carton. Accordingly, automatic high speed folding equipment can be used to close the flaps.

The entry opening weakened lines formed in the wall adjacent the tear strip wall are shown more in detail in the perspective view of FIG. 3. The lapped inner end wall flaps 50 and 52 are shown in lapped secured relationship. The weakened lines 26 and 27 are formed in the

inner and outer front wall panels 46 and 47, respectively, and extend to the longitudinal hinged line 37. The first infolded outer lap 54 has a weakened line 57 formed thereacross extending from the corner edge of the carton in approximate registry with the end edge of the inner wall flaps 50 and 52 to almost the free edge of the respective flap to define a removable tab section 58. The second folded outer end wall flap 55 has the bell shaped weakened line 28, previously mentioned, which extends to approximately the inward dimension of the inner end wall flaps 50 and 52 from the opposite corner edges of the carton. This provides that the tabs 29 and 58 can be rather easily separated from the end wall by pressing inwardly of the carton to expose the tear strip 24, which can then be grasped by the thumb and first finger to pull 15 in an outward direction along the weakened lines 26 and 27 to open the carton (see FIG. 4).

An alternate embodiment of end closure arrangement is shown in FIG. 5 which additionally includes an alternate initial entry construction to the tear strip. The embodiment shown in FIG. 5 is a gusset corner construction having converging hinge lines 63 extending across the end wall flaps 50a and 52a from the corners of the carton to a point at the free edge of the flaps to define thereby inner triangular panel 64 and intermediate triangular web panels 65. The web panels 65 are connected to the outer panels 54a and 55a on score lines 66. The gusset operates in a well-known manner in that the inner triangular panel 64 is initially folded across the open end of the carton construction, and the intermediate web panels 65 are extended in substantially flush relationship thereto and are sandwiched between the outer end wall panels 54a and 55a. A weakened line 28a is formed in the top wall panel 12a and is in direct communication with the exposed end edge of the lapped inner and outer front wall panels 46a and 47a of the tear strip 24a. The tear strip is defined between weakened lines 26a and 27a formed in the end wall panels.

In both disclosed embodiments, it is noted that the tear strip is formed along the manufacturer's joint of the tubular carton body and thus leaves unimpaired the end closure flaps for the tubular body. In such a case, the end closure flaps can be readily folded across the open tubular ends of the carton with automatic high speed flap folding equipment without causing flap buckling or defective closure of any kind. Full end closure sealing thus occurs across the end wall panels to provide both improved product protection within the carton and appearance of the carton.

What is claimed is:

1. An easy opening carton formed from an elongated unitary blank of foldable paperboard and including:
  - (a) opposed pairs of major and minor side walls hingedly interconnected to form a tubular structure;
  - (b) one of said minor side walls including a pair of inner and outer panels formed from end portions of the blank and hinged to corresponding side edges of respective adjacent major side walls;
  - (c) the panels of said minor side wall being secured

to each other in overlapped relation along a manufacturer's joint to form said tubular structure;

- (d) a pair of opposed end walls each including opposed pairs of end closure flaps hinged to corresponding ends of said major and minor side walls and adapted to be folded over and secured to each other in overlapped relation to close opposite ends of said tubular structure;
- (e) said panels of said one minor side wall having weakened lines formed therein and spaced from each other to define a tear strip in said minor side wall along and about said manufacturer's joint;
- (f) one of said walls adjacent said one minor side wall having a detachable section formed therein contiguous to said tear strip to provide a lead-in to said tear strip to facilitate easy opening of the carton by separation along said weakened lines of said tear strip.

2. A carton according to claim 1, wherein the weakened line in each panel of said one minor side wall which form the tear strip is spaced inwardly from the free edge of the panel and in substantial alignment with the free edge of the related panel, and wherein said weakened lines extend substantially across said minor side wall.

3. A carton according to claim 1, wherein said detachable section is defined by aligned weakened lines of tear in the end wall flaps which are hinged to said major side walls.

4. An easy opening carton formed from an elongated unitary blank of foldable paperboard and including:

- (a) opposed pairs of major and minor side walls hingedly interconnected to form a tubular structure;
- (b) one of said minor side walls including a pair of inner and outer panels formed from end portions of the blank and hinged to corresponding side edges of respective adjacent major side walls;
- (c) the panels of said one minor side wall being secured to each other in overlapped relation along a manufacturer's joint to form said tubular structure;
- (d) a pair of opposed end walls;
- (e) said panels of said one minor side wall having weakened lines formed therein and spaced from each other to define a tear strip in said minor side wall along and about said manufacturer's joint;
- (f) one of said walls adjacent said one minor side wall having a detachable section formed therein contiguous to said tear strip to provide a lead-in to said tear strip to facilitate easy opening of the carton by separation along said weakened lines of said tear strip.
